VALVE APPARATUS.

Application filed June 15, 1925. Serial No. 37,336.

This invention relates to improvements in valve apparatus. More particularly it relates to valve apparatus for testing the readiness of the pump to operate, in an automatic sprinkler system employing a pump for boosting the system pressure from a low pressure in the source of supply to a high pressure in the distributing lines, whenever discharge through a sprinkler head occurs. 5
Booster systems make automatic sprinkler protection possible in fire risks where the supply pressure from the city main or other source is too low for effective sprinkler service, and where the structural weakness of 10 the risk makes it impracticable or financially prohibitive to use a large gravity tank. Such systems, whether of the wet or dry pipe type, include between the supply main and the distribution pipes a normally inactive 15 pump and control means therefor, responsive to the system pressure for starting the pump whenever a sprinkler head is opened. Reliability being of the very essence, it is highly advisable to test such systems frequently. 20 The great cost of having experts visit each risk to make the tests locally, with desirable frequency, emphasizes the desirability to have several risks connected electrically with a central supervisory station by a device enabling a test of any individual risk to be made by a person at that station, whenever desired. Such a system is disclosed in United States Patent 25 No. 1,504,563, granted August 12, 1924, to Albert J. Loepsinger and entitled "Supervisory device for automatic sprinkler systems and the like." The test valve apparatus illustrated and described herein is particularly adapted for use in a supervisory system such as is disclosed in that patent; but other applications of its principles are possible for operating a valve located at a distance from the operator. For automatic 30 sprinkler systems the invention is applicable to both wet pipe and dry pipe arrangements.

An illustrative embodiment of the invention comprises a valve controlling an outlet from a sprinkler system whereby a situation may be produced simulating the conditions 35 that would exist in the system if a sprinkler head were opened by fire. The stem of this

valve is lifted by a lever which is a sort of connecting rod to translate the rotary motion of a crank into reciprocating motion of the stem, to open or close the valve. The 55 crank is turned through a single rotation by suitable gearing, driven by a small electric motor which starts in response to an impulse relayed from a remote central supervisory station. The crank arm is a disk whose 60 peripheral edge constitutes a series of cam surfaces adapted during a single rotation to make and break certain circuits controlling the motor.

In the embodiment illustrated, which is 65 suitable more particularly for a wet pipe system, the disk pauses at the end of a half rotation with the test valve open. After time when the pump should start, the disk is moved through its remaining half rotation 70 to close the valve, and then it is stopped until another test is initiated. The pause can be omitted and the rotation of the disk made continuous and such embodiment of the invention is disclosed in my co-pending 75 application for patent, Serial No. 35,837, filed June 8, 1925, where the invention is generically claimed. The present patent is specific to apparatus having provision for a pause in the movements of the disk. It is a 80 feature that during its operations the disk controls circuits connected with a water flow alarm device, to the end that the flow of water incident to the test shall not send a water flow signal to the central station, such 85 as occurs when a sprinkler is opened by a fire, nor permit a supplementary control circuit to be made whose normal function is to maintain the pump continuously in operation once it has been started.

It is intended that the patent shall cover by suitable expression in the appended claims whatever features of patentable novelty exist in the invention disclosed.

In the accompanying drawings: 95

Figure 1 is an elevation of a booster pump sprinkler system of the wet pipe type embodying the test valve of the present invention, and shows more or less diagrammatically the local circuits at a risk and also the 100 main transmitting wires connecting it and a neighboring risk with the central station;

Figure 2 is an elevation of the test valve of Figure 1 and actuating mechanism therefor, showing the valve closed;

Figure 3 is a view similar to Figure 2, but with the valve shown open, and

Figure 4 is a side view in section on line 4-4 of Figure 2, with the wires omitted.

Referring to the drawings, Figure 1 shows somewhat diagrammatically a supervisory circuit L leading from a central office A, through a risk B to another risk C where the sprinkler system to which the invention is applied is particularly illustrated as comprising a booster pump 10 set between a low pressure supply main 12 and a riser 14 having distributing pipes 16 leading to automatic sprinkler heads 18 located in various parts of the building comprising the risk. The system up to a water flow alarm check valve 34 stands full of water at whatever pressure may exist in the supply main, which is assumed to be too low or uncertain for effective sprinkler discharge. Beyond the valve 34 the system is charged with water and incidentally entrapped air at a pressure set up by the pump during a previous period of operation. Connected to the riser, above the valve 34 is a surge tank 20 in which is entrapped a body of air that transmits the system pressure to a pressure-responsive control device 22 adapted upon fall of the pressure to a predetermined degree, such as follows the opening of a sprinkler head, to close an electric circuit a through the field of a solenoid switch 24. The energization of this field causes its armature 26 to be moved so that a cross bar 28 connects a wire b leading from one of the power mains M, with a wire c running to a starter rheostat 30 controlling the pump motor 32. The pump 10 is thus put into operation to draw water from the supply pipe 12 and force it into the riser and distributing pipes at the boosted pressure. As the water flows upward in the riser it opens the check valve 34, and thus causes a water flow signal to be sent to the central office by suitable transmitting apparatus T, more fully described hereinafter. In making a test of the booster system it is desired to reduce the distribution system pressure sufficiently to bring about operation of the pump, as though a sprinkler head had actually opened, and yet to prevent a water flow signal from being transmitted while the test is being made as in the particular apparatus illustrated the apparatus which transmits such a signal simultaneously sets other apparatus for keeping the pump running continuously until it shall be stopped by an operator manually, as in the case of actual occurrence of a fire.

The test valve apparatus of the present invention accomplishes this double purpose automatically when the inspector at the central station A operates the apparatus there,

as by winding and releasing a transmitter key which sends out the proper impulse along the main line L to actuate momentarily the selector S of the local system that is to be tested. In thus operating, the selector closes 70 a circuit leading from one side of the main power circuit along the wire d through the now closed controlled switch 38, thence along wire e through test valve motor 36 (Figure 2) and thence back along wire f to 75 the other side of the power circuit. The test valve motor is thus started; and through a worm 40 on its shaft, and a gear 42 on an auxiliary shaft 44, it drives the latter which, through another worm 46 and gear 48 turns 80 the crank 50. This latter is in the form of a disk having a pin 52 outstanding from its flat surface and projecting through a slot 54 in one end of lever 56 which at its other end is pivotally mounted on the casing 58 and 85 which intermediately is connected to the stem 60 of the test valve 62. As the crank disk turns counterclockwise during one-half of a rotation it swings the lever 56 to open the test valve (see Fig. 3) and during the 90 other half rotation to close it.

As soon as the key at the central office runs down, which occurs soon after the test valve motor has started, the selector S' ceases to be energized and the switch 38 95 which it controls is again opened. This would stop the test valve motor were it not for other means which keep the circuit through the motor closed. These means comprise a wire g branching from main wire 100 d ahead of the selector controlled switch 38 and leading to one terminal 64 of a spring switch m which carries an arm and roller 66 positioned to engage the peripheral edge of the crank disk 50. This disk edge is 105 formed with two diametrically opposite depressions or hollows 50^a and 50^b into which the roller 66 may be sprung, by resiliency of its terminal bar 64, deeply enough to separate itself from the other terminal 68 of 110 switch m as the latter terminal is held by its stop 68'. The two sections of peripheral edge of the disk 50 between these depressions 50^a and 50^b constitute cam surfaces 50^c and 50^d, which are high enough to cause the 115 switch m to remain closed while the roller 66 rides upon them. A branch wire e' leads from the terminal 68 to wire e and the circuit continues thence through the valve operating motor and wire f back to the main 120 leads. The function of this spring switch m and its circuit is to maintain the motor running during a half rotation of the disk 50 after it has been started by some other agency, but to let it stop at the end of each 125 half revolution, at 50^a and 50^b. That is, when the selector S is operated from the central station and closes the circuit through switch 38, the valve motor will promptly start; and as the parts are so arranged that 130

its first turnings will rotate the crank disk 50 far enough to cause the roller 66 to ride out of the depression 50^a and on to the cam surface 50^c before the switch 38 opens, 5 the switch *m* will be closed in season for the circuit through it to keep the motor running, which continues until the roller has fallen into the depression 50^b. Thereby the switch *m* is opened; and the valve motor 10 stops, leaving the crank disk with pin 52 at the top of path and the test valve wide open as seen in Figure 3, a condition which is to continue until the test has progressed far enough to start the pump, so that it is desired 15 to close the test valve.

The consequent discharge from the system, through the test valve thus opened, lowers pressure therein until that point is reached at which the responsive device 22 20 is actuated to close the circuit *a* through the solenoid 24, thus starting the pump.

Beside the contact bar 28 on the armature 26 which spans the terminal points of the pump motor circuit, there is another contact 25 bar 28' which connects another terminal on the wire *b* from the main lead with a terminal on a wire *h* which leads through a second spring switch *n* located below the crank disk just ninety degrees from the spring 30 switch *m* first described. This switch *n* also has a roller 70 which rides on the peripheral edge of the disk 50 and is adapted when a suitable cam surface is encountered to press terminal 72 against terminal 74. The latter 35 is connected to a branch *e''* from branch *e'* of the wire *e*, so that when the switch *n* is closed, and the bar 28' spans wires *b* and *h* a circuit through the valve motor is established. When the test valve 62 is closed, and 40 the roller of spring switch *m* is in the depression 50^a, the spring switch *n* is open, because the cam surface 50^c against which the roller is then resting is of such radius, and the switch *n* is so set with relation to 45 it, that the roller terminal 72 is separated from the terminal 74 which is held by its stop 76. Accordingly if while the test valve is closed a sprinkler head opens, and the responsive device 22 acts to energize the 50 solenoid field 24 and to place bar 28' across the terminals of wires *b* and *h*, the test valve motor will not be started because at that time the switch *n*, and the switch *m* will both be open and no circuit through the 55 motor will be made.

However, when the test valve is open, (Figure 3) and the roller 66 is in the depression 50^b, the roller 70 will be against cam surface 50^a and the switch *n* will be closed 60 since this is of greater radius than the opposite surface 50^c. As the pressure of the system falls, due to the open test valve, the responsive device 22 actuates the solenoid and causes the contact bar 28' to span the 65 terminals of the wires *b* and *h*; and since

switch *n* is now closed the circuit thence through wires *e''*, *e'* and *e* and *f* is complete. This starts the test valve motor through the second half of its rotation, to close the test valve. Its initial movement closes switch *m* 70 and thus assures a full half rotation of the crank disk. Before this is completed the switch *n*, will have opened thereby breaking the circuit through the solenoid bar 28' so that even if the pump 10 is still running 75 and the bar 28' still in contact, when the test valve is again closed the test valve motor will be stopped when roller 66 drops into the hollow 50^a. In fact, however, if the turning of the disk 50 is so slow, and the action 80 of the starter and pump so rapid, in the apparatus portrayed, that if the apparatus is in proper working condition the pump will have raised the system pressure sufficiently to affect the pressure responsive device 22 so as to de-energize the solenoid and let bar 28' drop from the terminals of wire *b* and *h* by the time the test valve is again closed. This closing of the test valve is predicated upon the mere making of electrical 85 connections to start the pump, and is not of itself dependent on the actual starting or effectiveness of the pump as a condition precedent, the occurrence of those facts being made known by other means. If for 90 any reason the pump apparatus is not working, or the test valve does not automatically close, the operator at the central station can close it by again energizing the selector S. This he will do if a signal is not sent 95 by pressure rise device 78 and transmitter 80, showing the pump has restored the system pressure.

Thus the test-valve motor is (1) started by the central operator, (2) is maintained in 105 operation by switch *m* until the crank disk 50 has made a half rotation and opened the test valve 62, (3) is stopped by switch *m* when the roller 66 falls into hollow 50^b, (4) is again started by the combined control 110 of the solenoid switch bar 28' and switch *n*, as the pump starts, (5) is maintained in action during the remaining half rotation by switch *m* and (6) is again stopped by the opening of switch *m* when the roller 66 enters hollow 50^a, following the earlier opening of the switch *n*. The switch *n*, being open whenever the test valve is closed, prevents starting of the valve motor in case the solenoid field 24 is energized by the responsive device 22 following the opening of a 115 sprinkler in case of fire.

As previously stated the function of the test valve apparatus is two fold, first to release pressure from the system and establish 125 a condition simulating that which follows the normal opening of a sprinkler, and second to prevent a water flow signal going to the central office while a test is being made. The latter feature will now be explained. 130

The local water flow signal circuit is of the self supervising type comprising a double loop from one to the other of the spring terminals 82 and 84 of the water flow switch 5 *p*. One of these circuits or loops includes the battery *B* and the other includes the transmitter *T*. While the switch *p* is open, current flows in both of these circuits and the solenoid of the transmitter is energized. 10 When the switch *p* is closed, as by the opening of the valve 34 when water flows past it, the loop of the circuit through the transmitter *T* is short circuited, the solenoid becomes de-energized, its armature falls and the signalling mechanism 86 of transmitter *T* is actuated to send a water flow signal to the central office, which signifies the opening of a sprinkler, usually by a fire. Also as the spring wound key 87 of the transmitter runs 15 down, an insulated finger 89 comes to rest against one terminal 91 of a spring switch and holds it in contact with the other terminal 93 thereof, thus completing a circuit through wire *q*, battery *r*, wire *s*, solenoid *t* 20 and wire *u*. The armature 95 of this solenoid *t*, is moved to span the terminals of wires *b'* and *c'* connected in parallel with the wires *b* and *c* leading from the pump motor starter. Accordingly the circuit 25 through the motor is maintained even though later, upon rise of system pressure, the responsive device 22 is reset in non-pump-operating position, freeing the armature 28 from contact with the terminals of 30 wires *b* and *c*. Consequently if the water flow valve is opened and closes the spring switch *p*, not only will a water flow signal be transmitted but the pump will thereafter be operated continuously until the system is 35 manually reset.

In order to prevent such effects during a test it is necessary to render the circuits in the loops temporarily irresponsive to the closing of the water flow switch 34. This 40 the present invention accomplishes, by providing in the test valve casing a series of spring switches, whose opening or closing is controlled by the crank disk in its rotation. When the test valve is closed, and the system is ready to respond in case a sprinkler 45 head is opened by fire, the higher cam surface 50^d is uppermost as seen in Figure 2. Resting on this surface is a roller 88 whose arm is attached to a spring contact bar *i'* 50 whose end has a double contact point, one side of which is pressed against a contact point on another bar *j'* when the roller is on the cam surface 50^d. Between the bar *j'* and another bar *k'* adjacent to it, is an insulating 55 block 90 which separates the two and against which both yieldingly press. Accordingly 60 the pressure of the spring bar *i'* against the bar *j'* is transmitted by the insulating block 90 to the bar *k'* and holds its terminal point 65 against still another bar *l'*. Thus when the

roller rests on the cam surface 50^d the bars *i'* and *j'* will be in contact as well as the bars *k'* and *l'*. The bar *j'* is connected to the wire *j* leading from one terminal 82 of the alarm valve switch *p*, and the bar *i'* is connected 70 with wire *i* leading through the transmitter *T* to the other terminal 84 of the alarm switch, making one loop of the self supervising circuit. The bar *k'* is connected to a second wire *k* leading away from the terminal 82 and the bar *l'* is connected to a second wire *l* leading through the battery *B* back to the other terminal 84, thus forming the second loop of the self supervising circuit. Consequently, when the test valve is closed, and 75 the contacts made as just described, the two loops of the local water flow alarm circuit are made. Should the water flow valve 34 open, the water flow switch will short circuit the loop through the battery and thus de-energize the solenoid loop and cause a water flow signal to be given.

When the test valve motor has been started and has moved the crank disk through one half rotation to open the test valve the 80 cam surface 50^d of the crank disk will have moved into contact with the roller 88 as seen in Figure 3. The bar *i'* will have sprung downward and its terminal will have been separated from the bar *j'* because the latter 85 will have come in contact with its stop 92 before the downward swing of the bar *i'* is completed. Similarly the bar *k'* will have moved away from the bar *l'* as the latter engages its stop 94. Consequently upon the 90 roller 88 passing from the cam surface 50^d to the cam surface 50^e connections between wires *i* and *j* and between *k* and *l* will have been broken. Before the separations of bars *i'* and *j'*, during their first downward swing 95 together before the stop 92 is reached, the double contact point of the bar *i'* will have come in contact with the bar *l''* just below it. This contact will continue after the bars *i'* and *j'* and *k'* and *l'* have separated. As a result, since bar *l''* is also connected to wire *l*, the alarm valve switch is now rendered inoperative because the self supervising current now flows through bars *i* and *l''* and the wires *i* and *l* and through both the battery 100 and transmitter and these circuits are in no way interrupted by the closure of the alarm flow switch. Accordingly upon the water flow valve opening, as the booster pump forces water through the riser during the 105 test, and the water flow switch terminals are closed, there is no interruption of the self supervisory circuit through the transmitter, because of the connection between the wires *i* and *l*. Thus the second function of the 110 test valve apparatus is performed, and no water flow signal can be sent while the test is being made, nor will the pump be put in continuous operation.

When the crank disc is again rotated a 115

half revolution to close the test valve, the roller 88 will be raised by the cam surface 50^a and the bar *i'* placed in contact with the bar *j'* before the former separates from the 5 bar *l''* upon the latter reaching its stop 96. Thus the self supervisory water flow circuit will be maintained through one connection or the other of the switches as these connections are changed during the rotation of the 10 crank disk.

I claim as my invention:

1. Valve apparatus comprising a valve; a movable element having operating connection with the valve and adapted in a single 15 complete movement to effect a complete cycle of operations of the valve; means for setting the element in motion through a predetermined portion of its complete movement to a stopping position with partial operation of 20 the valve; and other means whereby a predetermined result of said partial operation of the valve puts the element in motion from said stopping position to complete its movement.
2. Valve apparatus comprising a valve; a movable element having operating connection with the valve and adapted in a single complete movement to effect a complete cycle of operations of the valve; power means for 30 moving said element; means for energizing said power means to start the element; means controlled by the element for de-energizing said power means after a predetermined partial operation of said valve, thereby to stop 35 said element; and other means whereby a pre-determined result of said partial operation of the valve again energizes the power means to set the element in motion to complete its movement.
3. Valve apparatus comprising a valve; a rotating element having operating connection with the valve and adapted in a single rotation to effect a complete cycle of operations of the valve; means for starting said 45 element through a partial rotation to a stopping position with the valve in shifted position; and means affected by conditions resulting from the shifted position of the valve for causing rotation of said element from the 50 said stopping position to complete its rotation.
4. Valve apparatus comprising a valve; a rotating element having operating connection with the valve and adapted in a single 55 rotation to effect a complete cycle of operations of the valve and whose peripheral edge constitutes a cam surface; an electric motor for rotating said element; means for energizing said motor; a switch controlled by 60 said cam surface for continuing said energization for a predetermined period to shift the valve and then de-energizing the motor to effect a pause in the operation of the valve; and means, affected by conditions resulting from the said shifting of the valve,

for again starting the rotation of said element to complete the cycle of the valve.

5. Valve apparatus comprising a valve; a motor; mechanism connecting them adapted to open and close the valve upon operation of 70 the motor and comprising a crank disk whose peripheral edge constitutes a cam surface; an electric circuit adapted to transmit an impulse for starting said motor; a supplementary circuit through said motor having 75 a switch controlled by the cam surface, the said cam surface being arranged for closing said switch upon starting of the motor and holding it closed during a partial rotation of the disk during which the valve is shifted, and for then opening the switch to stop the motor; means for re-energizing said motor upon the occurrence of a predetermined result of the shifting of the valve; said cam surface being further arranged for 80 again closing the said switch and holding it closed during the completion of the disk's rotation, and then opening the switch at the end of said rotation to stop the motor.

6. Valve apparatus as in claim 5, characterized by the two said switch closing portions of the cam surface being of different elevation; and the said means for re-energizing the motor being a switch arranged to be engaged by one elevation and not by the other; and said other elevation not engaging it, being toward it at the time of completion of said rotation, and that which engages it being toward it at the end of said partial rotation.

7. The combination, with an automatic sprinkler system having a pump for boosting the supply pressure, and control means for said pump including a device responsive to change of pressure, of apparatus for testing said system, comprising a valve controlling the pressure in said device, thereby to start the pump; means operating said valve, comprising a rotating element which in a complete rotation effects a complete cycle of valve operations; means for starting rotation of said element; means controlled by the element for stopping its own motion when the said valve has been shifted so that a change of pressure will be effected in said device to start the pump; and means, affected by actuation of said device, for starting the element to complete its rotation, thereby to shift the valve back to initial position.

8. The combination, with an automatic sprinkler system having a pump for boosting the supply pressure, an electric motor to drive it and control means for said motor including a device actuated by a drop in system pressure, of apparatus for testing said system comprising a valve controlling an outlet from said system and adapted upon being opened to effect a change of system pressure whereby said device is actuated to start the pump; means for opening and closing said

- valve comprising a rotating element which in a single complete rotation effects a complete cycle of valve operations; means extending to a distance for setting said element in rotation; means controlled by the element for stopping itself with the said valve open; and means, affected by the actuation of said device for starting said element to complete the rotation.
9. The combination, with an automatic sprinkler system having a pump for boosting the supply pressure, electric means driving said pump, a power circuit therefor having a switch, a supplementary circuit controlling movement of said switch, and a device responsive to change in pressure for governing said supplementary circuit; of apparatus for testing said booster, comprising a valve controlling an outlet from said system and adapted upon being opened to effect a change of system pressure whereby said device is actuated; means operating said valve comprising a rotating element which in a single complete rotation effects a complete cycle of valve operations; a motor for driving said element; means extending from a remote station for energizing said motor; means controlled by said element for de-energizing its said motor when said element has rotated far enough to shift said valve; and means for re-energizing said motor for completing the rotation, rendered effective by movement of said switch, upon response of said pressure device following the initial rotation and shift of the valve.
10. The combination, with an automatic sprinkler system having a pump for boosting the supply pressure and means whereby fall of system pressure starts the pump, and a testing valve arranged to produce a fall of system pressure, of means acting when the valve has been opened, to hold it open until the pressure has fallen to a predetermined extent and then to close the said valve.

Signed at Providence, Rhode Island, this 17th day of October 1924.

IRVING W. KNIGHT.
